Letters Patent (Design No. 79) dated Aug 18th 1845 and dated
June 1st 1846

The Schedule referred to in these Letters Patent
and making part of the same.

To all whom it may concern:

Be it known that I, Samuel H. Vose of Albany in the County
of Albany and State of New York, have invented or produced
a new ornamental design for a cooking stove; and I do hereby declare
that the accompanying drawings are full and accurate representa-
tions thereof, Fig. 1 being a front, Fig. 2, a side; and Fig. 3, a rear
view. Both sides bear the same figures - a is a section of the
mouldings upon the edges of the oven and fire doors: b those of
the panels at the back of the stove: c of the narrow panel to over
the front fire doors; and d those of the two panels to upon each
side of the same. The panels are filled with ornamental figures
composed of scrolls and foliage, not easily described in words,
but fully exhibited in the drawings.

What I claim as my invention and desire to secure
by letters patent, is the combination and arrangement of ornamental
figures exhibited in the accompanying drawings, forming an ora-
mental design for a Cooking Stove.
